UNITED STATES PATENT OFFICE.

GEORGE HAZELTON, OF PARIS, FRANCE.

MACHINE GUN AND THE LIKE FIREARM.

Application filed September 24, 1923. Serial No. 664,552.

To all whom it may concern:

Be it known that I, GEORGE HAZELTON, a subject of the King of Great Britain and Ireland, and residing at 7 Rue Georges Ville, Paris, XVIe, France, have invented certain new and useful Improvements Relating to Machine Guns and the like Firearms, of which the following is a specification.

The object of this invention is to prevent 10 the entrance of dust or water to the interior reciprocating mechanism of a machine gun by way of the slot through which the cocking handle of the gun projects and along which it slides when the gun is in operation.

15 The invention consists in a movable shutter lodged in a cavity in the breech body which entirely closes the said slot when the cocking handle is in its uncocked position of rest and is automatically displaced laterally 20 against the resistance of a spring to permit the movement of the cocking handle.

The invention also consists in a detachable cover plate fitted to the breech body and retained in position by a spring arranged to 25 permit the assemblage and removal of the shutter and spring.

A constructional form of the improved device according to this invention is illustrated by way of example in the accompanying 30 drawings in which:—

Figure 1 is an elevation of the breech, the shutter or slide being shown in a section taken through its vertical plane of symmetry with the cocking knob in its "rest position."

35 Figures 2 and 3 are similar views respectively during the movement of the knob, and when the latter is in firing position.

Figure 4 is a cross-section of the breech taken through the line A—A of Figure 1, 40 showing the cocking knob in the "rest position."

Figure 5 is a similar section taken through B—B.

Figure 6 is a longitudinal section taken 45 through the line C—C showing the lid in section and with its locking spring.

Figure 7 is an underside view of the lid.

Figure 8 is an elevation of the breech case showing the lid and the cocking knob.

50 In carrying my invention into effect in the form illustrated in Figures 1—8 the shutter 1 is a bar of rectangular section of length equal to that of the slot along which the cocking handle slides, and is provided with 55 a groove 2 along one of its long narrower

faces in which a long spring wire 3 is lodged. The shutter 1 is lodged in a cavity 4 at the side of the breech body having a plane face parallel to the plane of symmetry of the breech body. The slot 6 along which the 60 shank of the cocking handle slides gives communication between the said cavity and the bore of the breech body. A cover plate 9 is fitted to the breech body extending beyond both ends of the said cavity, is slid into 65 position from one end along grooves in the breech body and is retained in position by a small spring plate 11 fixed to the latter which engages with a hole 13 near the inner end of the cover plate 9. The entire upper edge of 70 the cover plate engages with a groove on the upper wall of the shutter cavity 4 but its lower edge extends at such distance from the lower wall of the cavity as to permit the shank 7 of the cocking knob 8 to slide easily. 75

The shutter 1 fits easily between the plane face aforesaid of the breech body and the parallel inner face of the cover plate 9. It is provided with a notch 15 near its forward end which, when the cocking handle is in 80 its forward position of rest (Figure 1) fits over the shank 7 of the cocking handle, thus permitting the shutter 1 to move downwards until its lower long narrower face is in contact with the lower wall of the shutter 85 cavity 4.

In this position the slot aperture is entirely closed up, so that dust or water cannot enter. The shutter 1 is forced into this position by the long spring wire 3 which abuts 90 against the upper wall of the shutter cavity 4.

The shank 7 of the cocking handle in contact with the shutter when in the said position of rest is made with a bevelled surface 95 and the notch of the shutter is similarly shaped (Figures 1 and 2). Thus, as soon as the cocking handle begins to move rearwards from its rest position (Figure 1), either during the automatic operation of the gun or for cocking the gun, the shutter is displaced upwards against the resistance of the long spring wire 3 (see Figure 2). In the cocked position (Figure 3) the long spring wire 3 forces the forward end of the shutter downwards so that the slot aperture is partially closed. 105

To dismantle the shutter a pointed implement of any kind, such as the point of a cartridge, is pushed through the hole 13 in 110

the cover plate to release the spring plate aforesaid therefrom, whereupon the cover plate 9 can be slid along its grooves until clear of shutter cavity. The shutter 1 with its long spring wire 3 can then be removed laterally from the cavity 4.

Claims.

1. A machine gun or like firearm including a closing shutter and means continuously urging said shutter into a position where it covers the cocking handle slot, a bevelled notch in said shutter, a corresponding bevel on the cocking handle shank whereby in all positions of the cocking handle the slot in

which the shank thereof slides is covered by 15 said shutter.

2. A machine gun or like firearm including a closing shutter disposed within a cavity in the breech and a spring tending continuously to retain said shutter in register with the 20 cocking handle slot, a slidable cover plate for said cavity and a groove on said breech for the attachment or detachment of said cover plate.

In testimony whereof I have signed my 25 name to this specification.

GEORGE HAZELTON.
